UNITED STATES PATENT OFFICE.

BUNKER STEWART AND DAVID BAILY STEWART, OF GARDEN CITY, KANSAS.

MOTOR.

1,092,458.

Specification of Letters Patent.

Patented Apr. 7, 1914.

Application filed March 17, 1913. Serial No. 754,740.

To all whom it may concern:

Be it known that we, BUNKER STEWART and DAVID B. STEWART, citizens of the United States, and residents of Garden City, 5 in the county of Finney and State of Kansas, have invented a new and useful Improvement in Motors, of which the following is a specification.

Our invention is an improvement in 10 motors, and has for its object the provision of a water motor adapted to be arranged in a flowing stream and provided with vanes for engagement by the water to rotate the wheel, so arranged that on one side of the 15 wheel the said vanes will automatically take a position at approximately right angles to the direction of the flow, and on the other side will automatically take a position approximately parallel with the direction of 20 flow to offer the slightest possible amount of resistance to the said flow.

In the drawings:—Figure 1 is a top plan view of the improved motor, and Fig. 2 is a section on the line 2—2 of Fig. 1.

The present embodiment of the invention 25 comprises a vertical shaft or standard 1, supported by a base 2, adapted to be arranged on the bottom 3 of a stream, and upper and lower frames are journaled on the standard or shaft. Stops 4 and 5 are arranged on the shaft or standard, the stop 4 being near the upper end thereof, while the stop 5 is near the lower end. Each of the 30 frames before mentioned, comprises a hub 6 engaging the shaft above the adjacent stop, and concentric rings 7 and 8 respectively are connected to each other and to the hub by spokes 9. The rings 7 and 8 are also connected by spokes 10, the said spokes being arranged intermediate the spokes 9. The spokes 9 in the present instance are arranged at angular distances of 90° and the 35 spokes 10 are also arranged at angular distances of 90° with respect to each other and at angular distances of 45° with respect to the spokes 9.

Two series of vanes are connected to the 40 frames, an inner series 11, and an outer series 12, the series 11 being arranged between the ring 7 and the hub, while the vanes 12 are arranged between the rings 7 and 8. Each of the said vanes consists of a plate of a length to extend from near the base 2 to above the level of the water, and 45 of a width corresponding approximately to

the distance between the rings, or between the inner ring and the hub.

The rings 7 and 8 are of such size that the rings 7 divide each of the spokes 9 into two approximately equal parts, that portion of 60 each spoke 9 between the hub and the ring 7 being of approximately the same length as that portion between the rings 7 and 8.

Each of the vanes 11 is hinged to a vertical rod 13, which connects the rings 7 of the 65 upper and lower frames, by means of hinges 14, the said hinges being secured to the vanes by rivets 15 and engaging the rod 13 near the ends thereof. Each of the said hinges 14 is adjacent to a frame, the upper 70 hinges being just below the ring 7 of the upper frame, while the lower hinges are just above the ring 7 of the lower frame. The vanes 11 are thus held in proper vertical position, and the said vanes are free to swing 75 on the rods. Each of the vanes 12 is connected to a rod 16 connecting the rings 8 of the upper and lower frames by means of hinges 17, the said hinges being secured to the vanes by means of rivets 18. The upper- 80 most hinge 17 of each vane 12 is arranged just below the ring 8 of the upper frame and the lowermost hinge of each of the said vanes is arranged just above the ring 8 of the lowermost frame. The hinges thus prevent 85 vertical movement of the vanes and hold the said vanes in proper vertical position.

The rods 13 are arranged adjacent to the 90 spokes 9 and in such position that the vanes 11 may be closed against the portion of the spokes between the ring 7 and the hub 6. The rods 16 are arranged adjacent to the outer ends of the spokes 9 and the outer 95 ends of the spokes 10 and in such position that the vanes 12 may close against the spokes 10 and against those portions of the spokes 9 between the rings 7 and 8.

All of the vanes are arranged on the same 100 side of the spokes and it will be evident that with this arrangement the vanes on one side of the wheel will be forced against the spokes of the frames by the current, while on the other side of the wheel the vanes will be forced away from the said spokes as 105 shown in Fig. 1. The rings 7 and 8 limit the opening movement of the said vanes.

A reference to Fig. 1 will clearly demonstrate 110 that when the wheel is in the position of the said figure, the two vanes adjacent

to the spoke 9, which is transverse to the current on one side of the wheel, will be at right angles to the direction of flow, and will be in contact with the said spokes. The 5 vanes on the opposite side of the wheel adjacent to the spoke 9 in alinement with the first-named spoke will be moved away from the said spoke 9 and will contact at their free edges with the rings 7 and 8. The said 10 vanes will not be precisely parallel with the direction of flow, but will be slightly inclined with respect thereto, so that the reaction of the current will tend to assist in the rotation of the wheel. A like statement 15 applies to the vane 12 immediately in advance of the first-named vane. The two vanes 11 and 12 on the up stream side of the wheel adjacent to the spoke 9 are also parallel with the direction of flow and offer no resistance to the current. As soon however, as 20 the vanes mentioned move away from a position exactly parallel with the current, the reaction tends to move the wheel forward, and the same statement applies to the vane 12 25 45° in advance. At no time is there more than one vane that offers any resistance to the forward movement of the wheel, and that is the vane adjacent to the spoke 9 on the lower or down stream side of the wheel 30 parallel with the direction of flow, and the said vane keeps this position but a slight length of time, soon moving into a position at right-angles to the direction of flow.

The improved motor may be used either

with water or any other liquid or fluid as 35 for instance air, and while the said motor is shown for convenience in a stream of water with its axis of rotation in a vertical position, it is obvious that the motor might be used with the axis of rotation horizontal, 40 and in the air, the motor being operated by the impingement of the air on the vanes.

We claim:—

A motor comprising a shaft or standard provided with spaced stops, frames supported on the shaft at the stops, each frame comprising a hub journaled on the shaft and rings arranged concentrically with the hub, spokes arranged at angular distances of 90° and connecting the hub and the rings, other 50 spokes arranged intermediate the first-named spokes and connecting the rings, said rings being of a diameter such that the innermost ring is at approximately half the distance between the hub and the outermost 55 ring, rods connecting the innermost rings adjacent to the first-named spokes, other rods connecting the outermost rings adjacent to the first-named spokes and adjacent to the last-named spokes, and vanes hinged to the 60 rods and of a width to close against the adjacent spokes, said vanes extending above and below the frame.
